CONDENSER AND SEPARATOR FOR
CRANKCASE VAPORSEstanislao Bogdany and Enrique Pedro Depouilly,
Buenos Aires, Argentina RepublicApplication June 3, 1934, Serial No. 729,726
In Argentina June 9, 1933

1 Claim. (Cl. 257—36)

This invention relates to devices for condensing oil from vapors originating in the crank case of an internal combustion engine and separating this oil so that the uncondensed vapors may be carried to and utilized in the carburetor of the engine.

The object of the invention is to provide an oil reclaimer and separator which is adapted at one end to be connected to the crank case of the engine and receive oil laden vapors therefrom and which at the other end is adapted to be connected to the carburetor of the engine, the separator itself constituting a casing through which the vapors travel in a circuitous course, the casing being intersected or traversed by closely adjacent air tubes extending entirely through the casing, preferably in the direction of travel of the automobile and being open at their opposite ends so that cool atmospheric air may pass thru these tubes and thus act to cool and condense the vapors carried into the casing.

Our invention is illustrated in the accompanying drawings wherein:—

Figure 1 is a side elevation of our reclaimer and separator, a side wall being partly broken away;

Figure 2 is an end elevation of the structure shown in Figure 1.

Referring to these figures, 1 designates the casing of our improved separator, this casing being preferably cubical in form and being relatively narrow. Extending through the casing from one end to the other and disposed very closely adjacent to each other are the air tubes 2, which open at their ends, as at 3, upon the front and rear of the casing so that as the automobile travels, fresh atmospheric air may be forced through these tubes 2.

The casing at one end is provided with an inlet opening in its bottom into which extends a pipe 8, which leads from the crank case of the engine (not shown). Extending from the top of the casing at the end opposite the inlet opening is the outlet pipe 9, which may lead to the carburetor of the engine. Extending upward from the bottom 10 of the casing is a baffle plate 6 which terminates short of the top of the casing and which is disposed just beyond the inlet pipe 8. Extending downward from the top of the casing is a baffle plate 7 which terminates short of the bottom 10 of the casing and which is disposed at its upper end adjacent the outlet pipe 9. The tubes 2 extend through these baffle plates 6 and 7.

By means of these baffle plates, the vapors passing from the crank case of the engine into the casing through the pipe 8 are caused to take a circuitous course upward, then downward and then again upward before passing out through the outlet pipe 9 and in this circuitous course the vapors come into intimate contact with the cool air pipes 2 and any oil or readily condensable liquid which may be carried in with the vapors is condensed and this oil drops downward onto the bottom 10. The bottom 10 is inclined, as shown in Figure 1, or sloped downward toward one end of the casing and at this end of the casing there is an opening discharging into a collecting receptacle 11, shown as supported by means of a 15 yoke 12. Oil may be drained from the collecting receptacle at any time for reuse.

It is designed that this casing be disposed closely adjacent to the engine so as to receive heat therefrom whereby the heat radiated from the 20 motor will induce an advantageous temperature in the chamber or casing.

We claim:

An oil reclaimer and separator for internal combustion engines, comprising a relatively narrow casing disposed in vertical position and having broad side walls and narrow top, bottom and end walls, said bottom wall being disposed at an inclination, air tubes extending through the casing between said end walls and parallel with the side walls thereof, a baffle plate extending upwardly from the bottom wall to a point short of the top wall and connecting the side walls and having the air tubes passing therethrough, a second baffle plate extending downwardly from the top wall in spaced relation with the first baffle plate and terminating short of the bottom wall and connecting the side walls and having the air tubes passing therethrough, an oil vapor inlet through the bottom wall adjacent the highest end thereof, an outlet for the casing through the top wall adjacent the opposite end from the inlet, said bottom wall at its lowest end having an outlet opening and a downwardly extending flange surrounding the same, an oil receiving cup having a mouth adapted to position over said last opening within the flange, and a ball oscillatably attached to said flange and adapted to be positioned beneath said cup to retain the latter in operative position.

ESTANISLAO BOGDANY.
